SLUB CATCHER

Jean Charles Plourde, Rochelle, Ill.

Application June 16, 1939, Serial No. 279,435

7 Claims. (Cl. 28—64)

The present invention relates to devices for attachment to and use on cone, skein, and tube winding machines, for detecting and preventing passage of enlarged imperfections known as "slubs" in thread or yarn.

The principal object of the invention is to provide such a device embodying means arranged to be thrown into operation automatically by contact with the slub to break the thread or yarn near the place where the slub occurs, thus enabling the operator to remove the objectionable unsightly slub portion so that it won't be wound onto the cone and be the cause of a flaw in the fabric knitted from the yarn.

Other objects and advantages of the invention will be apparent in the following description in which reference is made to the accompanying drawing, wherein:

Fig. 1 is a longitudinal section of the slub catcher;

Fig. 2 is a side view thereof;

Fig. 3 is a plan view thereof;

Figs. 4 and 5 are sections taken on the lines 4—4 and 5—5 of Fig. 2 looking in the direction of the arrows; and

Fig. 6 is a perspective view of the comb provided on the yarn cutting end of the slub catcher.

In thread and yarn it is not uncommon for defects and irregularities to occur which those in the trade refer to as "slubs." These usually take the form of an enlargement or a bunch in the yarn and are weak and of inferior quality, and are objectionable and unsightly in a finished product. The device of my invention is designed to detect these, cut the yarn, and give the operator a warning and opportunity to remove the objectionable part and tie the yarn. A knot is not objectionable in the finished product and does not show whereas a "slub" will. The slub catcher has adjustments which adapt it to various kinds and sizes of threads and yarns, including core yarn (combination worsted and cotton), cotton, silk and wool. The device may be used in connection with various kinds of winders, such as cone, skein, and tube winders, or wherever it is desired to avoid possibility of slubs passing.

A frame is indicated at 7 which supports the device and by means of which it may be attached to the machine it serves. At the forward end of the frame, i. e., the end from which the yarn travels through the slub catcher, is an eyelet 8 over which the yarn 9 is threaded as a guide. A wire bracket 10 is mounted at one end in boss 11 on the frame and extends substantially the

full length of the machine, and is mounted at its other end at 13 in the frame. Following in the direction of the travel of the yarn is a tensioning device 14 mounted on a boss 15 on the frame 7. It comprises a spindle 16 set into the boss and projecting therefrom vertically, over which is placed a sleeve 17 and two friction disks 19 pressed together by a weight 20. The disks are annularly flanged as at 21 so as to enable the yarn to be easily threaded therebetween. The yarn is drawn between the plates and the weight 20 may easily be changed or augmented to furnish a desired tension. Bracket 23 is mounted in the frame and has an angle portion 24 extending over the tensioning device 14 to prevent accidental removal of the weight or upper disk.

An arm 25 extends laterally from the frame on which is mounted a horizontal platen or guide 26 over which the yarn travels and which defines the lowermost level at which the yarn may travel in the slub catcher. Spaced a short distance from the arm 25 is a boss 27 which carries a guide arm 29 under which the yarn travels and which defines the uppermost level at which the yarn may travel in the slub catcher.

Rearwardly of this point is another boss 30 which supports a spindle 31 threaded for vertical adjustment and provided with a lock nut. A sleeve 33 is placed over the spindle and is provided with a flange 34 which supports a bottom plate 35 and a disk or two of wax 36. The yarn travels between the plate and the wax for waxing, and inasmuch as the wax is mounted loosely on the spindle it will revolve and wear off uniformly.

At the rearward end of the frame is an upwardly extending lug 37 from which projects a boss 39 carrying an adjustment screw 40 and a lock nut. An arm 41 is pivoted on bolt 43 and is provided with a laterally extending arm 44 on which is mounted a platen or guide 45. A coiled spring 46 is also mounted on bolt 43 and biases arm 41 upwardly while reacting against boss 39. Adjustment screw 40 defines the uppermost level to which the arm 41 may be raised and the lower edge of the platen 45 carried thereon serves as an upper guide for the yarn. At 47 and 48 are indicated two pins and at 49 a fork which serve to guide the yarn. Fig. 5 also shows the pins 47 and 48 and in this view can be seen a notch 50 cut into the side of pin 48 to limit the lateral movement of the yarn.

In accordance with my invention a lever 51 is provided extending lengthwise of the frame 7

and having depending ears 53 for pivotal support thereof on a bolt 54 mounted on frame 7. Rearwardly of the pivot 54 the lever 51 has a short arm 55 which is of appreciable width, as shown in Figs. 3 and 4, so that the yarn may move laterally in its travel through this device and still remain in contact with the arm 55. The other arm 56 is of much greater length and extends forwardly to a point near platen 26 where it carries a comb 57 made up of a series of sharply pointed pins placed side by side as shown in Fig. 6. Just rearwardly of the front end of arm 56 is a boss 59 projecting from frame 7 and provided with an upwardly projecting adjustment screw 60 and a lock nut. The arm 56 of the lever 51 in its retracted position rests on adjustment screw 60 and may be raised or lowered thereby to position the comb 57 just slightly below the level at which the yarn travels, as best appears in Fig. 1. Since the position of the rear arm 55 of the lever is determined by the position of the forward end, the platen 45 must be adjusted to allow for proper clearance between it and arm 55.

In operation, the yarn travels in the direction of the arrow 63 and passes through the space between platen 45 and lever arm 55. The arm 55 acts as a "feeler" adapted to detect any enlargement in the yarn. When a slub occurs in the yarn, its greater size will not permit it to pass through this space without moving the lever arm 55, since the platen 45 is fixed against upward movement. The instant the lever arm 55 is moved downwardly, arm 56 is moved upwardly and the pin points of comb 57 jab into the yarn and it is broken. Due to the angle of the pins of the comb 57 in relation to the yarn, the pins dig into the yarn with a force proportional to the tension or pull on the yarn as it is being wound. Since arm 56 is of much greater length than arm 55, a proportionately small movement of arm 55 is sufficient to move the comb 57 into the yarn, and a slub which results in only slight enlargement of the yarn will be easily detected. In passing, it should be understood that I may reverse the position of the slub catcher in relation to the direction of yarn travel, in which event the comb 57 would, of course, be inclined in the opposite direction. However, I prefer the arrangement shown.

Means may be provided so that when the yarn has been cut, winding or other operations of the associated machine will cease, as, for example, a brake device may be released to operative position upon movement of lever 51. Usually, however, a trip device automatically stops the machine upon release of yarn tension when the yarn is broken by the slub catcher, in the same way as when any other break in the yarn occurs, or when the end of the yarn is reached. Such automatic stop devices are so well known there is no need for further description. It suffices to state that the automatic stopping of the machine after breaking of the yarn by my slub catcher calls the attention of the operator to the slub detected so that no time is lost in removing a short length of yarn containing the slub whereupon the loose ends are tied with a French knot and the machine is restarted.

It will be seen that since tensioning means 14, plate 35 and wax disk 36, and platen 45 are all adjustable vertically a path may be established so that there is straight line movement of the yarn.

I do not intend to be limited to the specific de-

tails herein shown and described, but contemplate including within the scope of the invention all substitutions of equivalents and changes in details of construction and arrangement of parts to fit particular conditions.

What I claim therefore and desire to secure by Letters Patent is:

1. In combination, a frame, a yarn guide mounted on the frame and disposed in horizontal position, a lever pivoted on the frame on a horizontal axis and having a long arm and a short arm extending in opposite directions from the pivot, said short arm disposed below said guide and defining therewith a gap through which yarn may be drawn, said long lever arm gravitating to bias the short lever arm toward the guide, and a cutter mounted solely on the free end of the long lever arm and adapted to be thrown into the yarn and cut it upon upward movement of the long lever arm consequent upon downward movement of the short lever arm caused by the passage through the gap of an enlargement in the yarn.

2. Structure as set forth in claim 1 including means under the long arm for adjusting the same vertically so as to vary the spacing of the cutter relative to the yarn, said guide being also adjustable vertically and being arranged thereafter to be adjusted relative to the short arm to fit the yarn size to be operated with.

3. In combination, two longitudinally spaced yarn guides which determine the path of movement of yarn, a lever pivoted so that it has a short arm and a long arm extending in opposite directions from the pivot, the short lever arm disposed in spaced relation to one of said guides and defining therewith a gap through which the yarn of predetermined size is adapted to be drawn freely, said lever being normally biased in a direction to move the short lever arm toward the adjacent guide, the short lever arm being moved away from said guide upon the passage through the gap of an enlargement in the yarn, a cutter mounted solely on the free end of the long lever arm and disposed normally in spaced relation to the yarn adjacent the other of said guides, the long lever arm being moved toward the yarn upon movement of the short lever arm to throw the cutter into the yarn and cut it.

4. In an apparatus for detecting and catching slubs in a run of yarn passing therethrough, a frame, opposed guide means thereon defining a straight line path for the yarn therebetween, tensioning means for the yarn, a lever pivotally mounted on the frame beneath but adjacent the yarn run and providing a cutter arm and a feeler arm on opposite sides of the pivot, and a guide on the frame coacting with the feeler arm to define a gap through which the yarn is drawn, said lever being normally biased in a direction to move the feeler arm toward the guide, said cutter arm solely supporting on its free end a pronged device inclined at an acute angle relative to the yarn and pointing in a direction opposite to the direction of yarn movement, namely, away from the guide, and disposed normally out of contact with the yarn but adapted to be brought into contact with the yarn upon slight movement of the feeler arm.

5. An apparatus as set forth in claim 4, including waxing means for the yarn on said frame, located between the pronged device and the guide, whereby the pronged device is arranged to cut the yarn at a point ahead of the waxing means.

6. The combination set forth in claim 3, including means cooperating with the long lever arm to adjust the same to vary the spacing of the cutter relative to the yarn, the guide cooperating with the short lever arm being also adjustable relative thereto and being arranged to be adjusted after the adjustment of the last-mentioned means to fit the size of the yarn in connection with which the same is to be used.

7. The combination set forth in claim 3, including waxing means for the yarn, located between the cutter and the guide cooperating with the short lever arm whereby the cutter cooperates with the yarn before the yarn is waxed.
